To all whom it may concern;

Be it known that I, **FREDERICK WINK**, of the city and county of Philadelphia, State of Pennsylvania, have invented a Design for a Shawl-Pattern, of which the following is a specification:

being strongly contrasted and others blended into each other, as shown.

Irrespective of the colors employed, I claim—

The design for a shawl-pattern, as represented in and by the accompanying drawing.

In testimony whereof I have signed my name to this specification in the presence of two subscribing witnesses.
